SYRINGE

Fairleigh S. Dickinson, Rutherford, N. J.

Application November 13, 1931, Serial No. 574,764

2 Claims. (Cl. 128—215)

The invention relates to syringes and more particularly to syringes of the type comprising a glass barrel and plunger. The object of the invention is to provide simple, inexpensive, and efficient means for producing by a single instrumentality differential braking effects against the plunger, such that the plunger will be under moderate braking influence during the major part of its movement, while the braking strain is accentuated during the final movement of the plunger to its fully seated position in the barrel. According to the present invention the same structural elements are used for the establishment of the two different types of braking effect. The moderate braking effect will enable the physician or user to set or maintain the plunger at any desired point with respect to the dosage to be admitted to the syringe or to be ejected therefrom. The more intensified braking effect will not prevent the plunger from being fully seated in the barrel, but will, in the normal carrying position of the syringe, space the bottom of the plunger from the bottom of the barrel and prevent impacts due to vibration, or the like, from breaking off the ejection end of the barrel.

The invention is shown in the accompanying drawing in which Fig. 1 is an elevation partly in section showing the syringe with the parts in their normal position as carried by the physician or user. Fig. 2 is a similar view showing the plunger partially drawn out of the barrel. Fig. 3 is a sectional view showing the position of the parts when the plunger is fully seated and the full dose previously contained in the barrel has been ejected. Fig. 4 is a side view of the upper part of Fig. 1 and Fig. 5 is a sectional view on line 5—5 of Fig. 2.

In the drawing, 1 represents the usual barrel having an ejecting end 2, a duct 3, and, at the upper portion, a ledge or flange 4. The plunger 5 is provided with an enlargement or head 6. As shown in Fig. 5 the ledge 4 comprises two sections 4a which extend further from the axis of the cylinder than the straight sided sections 4b. The under sides of the portions 4a afford an abutment for the index and middle fingers of the operator while his thumb rests on the head 6 in ejecting fluid from the syringe. The parts 4b of the ledge are used in connection with the clip 7. The clip 7 is an integral piece of resilient metal stamped into the shape shown in the drawing and comprising the barrel-embracing portion 8, the portion 9 which engages the under surface of the flange 4, the portion 10 which engages the upper surface of the flange 4, the spring fingers 11 flexed

toward the axis of the barrel, and the obliquely and outwardly extending terminal portions 12. The portions 11 and 12 include the friction face 13 which, when in contact with the outer surface of the plunger, exercises a moderate braking effect, and the portion 14, which represents a cam face co-acting with the enlargement 6 of the plunger. In the described construction it will be noted that the parts 11, 12, 13, and 14 constitute upwardly rising extensions whose movements are limited to movements away from or at right angles to the axis of the plunger and that the parts thereof which have frictional activities, 13 and 14, are so arranged and positioned that they will operate as brakes against the plunger and as a means for normally preventing the plunger from contacting with the nozzle end of the barrel because of the tendency of the free terminal sections to move toward each other and because the resilience of their supporting components allows them to move apart, under forcible depression of the plunger head and to raise the plunger when the depressing force is withdrawn. It will further be noted that these upwardly rising extensions 11, 12, 13, and 14 are integrally connected with the barrel-embracing portion 8 by integral strip portions 9, 7, 10, of which the part 9 extends outwardly from the barrel beneath its ledge 4, forming a resilient hinge where 9 and 8 join. Thence the strips extend upwardly around the ledge and back again over the top of the ledge as at 10 in a direction toward the axis of the plunger. The result of this arrangement is that the normal braking action of the upwardly raising extensions 11 of the clip, in any intermediate position of the plunger with relation to the barrel (as indicated in Fig. 2), is a function of the resiliency of the extensions 11, while, when the extensions 11 of the clip are forcibly pressed apart (as shown in Fig. 3), the resiliency of the fingers 11 will be reinforced by the resiliency of the hinge connection between parts 9 and 8. When the operator removes his finger from the plunger head 6, the parts being in the position shown in Fig. 3, the combined resiliency of the hinge connection referred to and of the upward extensions 11 has sufficient pressing capacity to restore the plunger to the position shown in Fig. 1, after which, as the plunger is raised to a position such as indicated in Fig. 2, the resiliency of the extensions 11 alone is thereafter sufficient to supply the normal braking effects which hold the plunger in any more withdrawn position. In any event the extensions 11 at their free terminal regions not only

function constantly in all positions of the plunger 55

er but also do the whole of a diverse character of service, i. e. braking, cushioning, and lifting and accomplish this by the capacity of the extensions to move toward and to be moved away 5 from each other always toward and away from the axis of the plunger and not in parallelism to such axis.

In the manufacture of glass plungers, one end of a glass tube is heated, its end closed, and the 10 workman then blows a bulb at the closed softened end of the tube. This bulb is reintroduced to the flame, softened thereby, and the workman then closes a tool upon the softened bulb, the tool forming the head 6 and the neck 15. When 15 the glass is cooled, the workman tools it to close the other end in the flame and presses the bottom against a flat surface. When the thus formed plunger has cooled, the outer surface of its plunger section is ground. This method of forming 20 the plunger results in variations in the length of the ground section as well as the over-all length of the plunger. These variations are generally within narrow limits of one or two millimeters for plungers adapted to fit the same size of barrels. The construction of the clip 7, particularly 25 with respect to the cam faces 14, is consequently such as to function in the intended fashion, irrespective of whether the distance between the 30 under side of the enlargement 6 of the plunger and the bottom flat surface of the plunger is slightly greater or less than the particular distance illustrated in the drawing. In other words, the clip 7 is so made that it will fit any syringe 35 of the same type and do its work properly, notwithstanding the usual variations in the length of the plungers. A feature not so apparent but of material importance is that the neck 15 of the plunger is not to be made as narrow as is 40 now general practice, but shall at most be only slightly smaller than the cross section of the ground section of the plunger. This insures a continuance of the braking effect of the friction faces 13 after they leave the ground section of the 45 plunger and pass the shoulder 16 and during the time that the friction faces 13 are in contact with the neck 15 before the cam faces 14 begin to be acted on by the underside of the plunger head 6. By making the neck 15 at best but slightly 50 smaller than the ground section of the plunger, there is no sharp offset at the shoulder 16 so that the braking effect of the friction faces 13 continues smoothly and without jump. In other words, the upper portion of the plunger is specially fashioned to minimize any sudden alteration in the 55 braking effect of a braking instrumentality or clip which functions by virtue of the exercise of resilient pressure against the ground face of the plunger and may also at another stage of the 60 operation rest against a smooth face of a portion of the neck, or vice versa, in succession.

It will be observed that when the parts are in the normal, inactive position shown in Fig. 1, the 65 plunger is maintained out of contact with the ejecting end of the barrel and that irrespective of shocks, vibrations, rough transportation or the like, the plunger will be prevented from fully seating itself within the barrel and thereby protect the forward end of the barrel against breakage. When, however, it is desired to fill the 70 syringe, the operator has but to place a slight additional pressure upon the head 6, causing the resilient fingers of the clip to be cammed aside 75 as shown in Fig. 3, whereupon the plunger can

be withdrawn to any desired point and the syringe correspondingly filled with fluid. As the plunger is withdrawn, say to the position shown in Fig. 2, the friction faces 13 of the resilient fingers 11 will press against the outer surface of the plunger 5 and exercise a moderate braking effect sufficient to maintain the plunger at any desired position in the barrel, in the absence of applied pressure on the head 6, so that the physician may lay down the syringe and subsequently pick it up again 10 without fear that due to relative movement of the parts any change of the syringe has taken place. When it is now desired to empty the syringe, the thumb, pressing against the head 6, will cause the plunger to move down in the barrel and at the moment the position shown in Fig. 1 is reached, a slight additional pressure to overcome the accentuated braking effect of the cam faces 14 of the fingers 11 will permit the cylinder to be readily and gently brought to the fully seated 15 position shown in Fig. 3. After the syringe is cleaned and/or sterilized and redeposited in its case or in the physician's pocket, it will automatically assume and retain the condition shown in 20 Fig. 1 where, on the one hand, the plunger cannot fall or slide out of the barrel because of the checking effect of the fingers 11, while the plunger will not, on the other hand, be shakable into its fully seated position but will require positively applied pressure against the head 6 to 25 reach its fully seated position.

The barrel-embracing portion 8 of the clip is preferably rounded as shown in Fig. 3, to give it greater strength. The part 8 as shown in Fig. 5 35 has an inner wall approximating two-thirds of the outer circumference of the barrel. This makes it possible to seat and unseat the clip with great ease, due to its resilient characteristics, and yet, by virtue of the same characteristics, to hold 40 the clamp firmly in place on the barrel. The frictional contact face 13 of the fingers 11 may be flat or shaped to fit the sides of the plunger and they may have lateral projections to increase 45 the frictional surface, but these are details which are merely auxiliary and are therefore not illustrated.

As shown in Fig. 2 in contrast with Fig. 1, it will be observed that the spring fingers 11, when exercising their frictional effect on the outer 50 walls of the plunger, owe their braking effect chiefly to their own flexibility from the point where the fingers merge at a sharp angle with the portion 10 of the clamp. When the camming effect takes place, however, as shown in Fig. 3, 55 the resiliency is not only that of the fingers per se, but also that of the entire clip down to the angle where the portion 9 begins to extend away from the barrel-embracing portion 8, thereby accentuating the braking resistance of the clamp 60 against movement of the plunger from its position in Fig. 1 to its fully seated position.

In view of the patent to F. L. Wood No. 2,002,024, no claim is made herein broadly to the employment of a clip which is so arranged with 65 reference to the components of the syringe as to normally maintain the inner end of the plunger out of contact with the nozzle end of the barrel but still enables the plunger to be pushed all the way into the barrel of the syringe, but what is 70 claimed herein is the specific and novel arrangement described hereinabove and defined by the following claims.

I claim:

1. In a syringe of the type which comprises a 75

barrel having a nozzle end and a plunger end, a ledge projecting outwardly from the plunger end, a plunger having an enlarged head portion adapted to be pressed by the user, and clip means for maintaining the inner end of the plunger normally out of contact with the nozzle end of the barrel but yieldable to permit such contact to be made when desired, that improvement which comprises in the recited combination a clip structure of resilient material having a barrel-embracing portion seated beneath the ledge, a pair of diametrically opposed relatively flat extensions connected with said barrel-embracing portion and extending upwardly with their flat faces constantly facing the axis of the plunger to a height above the ledge greater than the height of the under side of the plunger head when the plunger is in contact with the nozzle end of the barrel, said extensions having terminals which flare outwardly from the axis of the plunger in opposite directions, all arranged so that each of said extensions with its terminal will be limited in its flexing movements to motions at right angles to the axis of the plunger and in directions opposite to that of the other extension, the extensions at their bent-back terminal portions acting as brakes against the plunger and as a means to resist complete descent of the plunger into contact with the nozzle end of the barrel except un-

der pressure of the operator and also to return the plunger, when said pressure is released, to the position in which the plunger end is maintained out of contact with the nozzle end of the barrel.

2. The combination set forth in claim 1 in which each of the upwardly extending flat resilient extensions is connected with the barrel-embracing portion of the clip by an integral strip which extends outwardly from the barrel beneath its ledge to form a resilient hinge, thence upwardly around the ledge and back over the top of the ledge in a direction toward the axis of the plunger whereby, as the plunger is positioned at any point intermediate of its complete stroke, the normal braking action of the upwardly rising extensions of the clip will be a function of the resilience of said portions, while, as said portions are forcibly pressed apart in the final seating movement of the plunger in the barrel, their own resilience is reinforced by the hinge connection with the barrel-embracing part of the clip, said reinforced resiliency serving as a combined force to withdraw the plunger to a position where its inner end is free from contact with the nozzle end of the barrel and where the parts are restored to the condition where thereafter the resilience of the extensions alone exercise their braking effect.
